UNITED STATES PATENT OFFICE.

ARCHA FAVOR, OF GALESBURG, ILLINOIS.

DEVICE FOR OPERATING AIR-COCKS ON AIR-BRAKE CARS.

No. 867,718.

Specification of Letters Patent.

Patented Oct. 8, 1907.

Application filed June 14, 1907. Serial No. 379,041.

To all whom it may concern:

Be it known that I, ARCHA FAVOR, a citizen of the United States, and a resident of Galesburg, in the county of Knox and State of Illinois, have invented 5 a new and useful Device for Operating Air-Cocks on Air-Brake Cars, of which the following is a specification.

My invention has relation to means for turning on or off (or, as it is termed by railroad men, "cutting in" or "cutting out") the air on air-brake cars.

10 On cars equipped with air-brake apparatus the angle-cock in which is seated the valve, is located to one side of the center of the car, or in other words, at the right hand side of the car-coupling. The air-hose extending from one to an adjacent cock is below the 15 coupling and angularly thereof, or crossing it. It will thus be evident that in cutting in or out the air by the employment of the ordinary wrench or spanner, the brakeman or other operator must reach across the car coupling in order to reach the distant angle-cock, 20 to the great endangerment of his limbs or even life. The hand lever now in use is necessarily very short, and because of the constant exposure of the car and the close fitting of the valve, it is often a difficult matter to operate the latter. The usual expedient 25 adopted is to reach up with the foot and kick the lever—another dangerous operation.

The primary object of the invention is to provide means whereby the operator may cut in or out the air without stepping between the cars, and in the 30 employment of which means all risk of injury is eliminated.

Another object is to provide means whereby the valve may be turned with but little effort.

Subsidiary objects will appear as the nature of the 35 invention is better understood.

The invention consists in novel constructions and combinations of devices, the operation of which devices will be found hereinafter fully described and set forth in the claims hereto appended.

40 Mechanism embodying the preferred constructive forms of, and showing the mutual relationship and combinations of the parts forming the subject matter of my improvements, is illustrated in the accompanying drawings, in which:

45 Figure 1 is a front elevation, partly broken away, showing my improvements as incorporated in a railway box-car furnished with air-brake equipment and the air (for instance) turned on. Fig. 2 is a front elevation, the parts in different relative positions from that shown at the principal figure, or cut off. Fig. 3 is a top plan showing the same parts as at Fig. 2, but in different relative positions, the valve being on a center, neither on nor off. Fig. 4 is a detail, an elevation of the rocker, seen from the side next the car,

and Fig. 5, a sectional view of the same, the view 55 being taken in the line x—x, Fig. 4.

In the drawings, to which reference is to be had in connection with the numerals of reference thereon, 1 represents the end of a box-car; 2, the "deadwood"; 3, the buffering plate; 4 and 5, other ordinary metallic 60 plates; and 6, the draw-head, all of which may be of ordinary construction and need not be further herein described.

7 indicates an angle-cock such as is in general use on appliances of this kind or character. It comprises 65 a tubular portion 8 which extends underneath and is supported by the car in any suitable manner, in which tubular portion the valve (not shown) is seated, and a threaded end or nozzle 9 to which a short section of hose 10 is coupled in the usual manner. It is furnished 70 with a semi-circular projection at its upper portion, the ends of which projection constitute abutments 11, for a purpose presently related. The valve-stem 12 (which is fixed to or integral with the valve) is located midway between the abutments 11 and projects a 75 slight distance thereabove. The last described parts are also well known constructions and form no part of my invention. A lever or other eccentric means, the head 13 of which is provided with a boss 14 is fitted snugly over the valve-stem 12 by means of an aperture 80 therethrough. Both are preferably angular in form for perfect operation, and are rigidly held from disconnection by means of a pin 15. The power arm 16 of the lever is split, and to it is pivotally connected the head of a pitman rod 17 which is provided at its distant end with a series of apertures 18.

Directed through brackets 19 at each side of the car are push or pull bars (as the case may be), 20, 21, each provided with a grip or handle 22 and each pivotally connected to one member of an adjustable rocker 23 90 which I shall now proceed to describe. 24 indicates a substantially U-shaped casing provided near its lower end and at one edge with an apertured lug 25, one of the walls 29 of the channel being here cut away. Projecting from its lower end is a pin or wrist 26 on 95 which a swivel-yoke 27 is mounted. It is provided with apertures 28 in its web for purposes presently described. Held in place in the channel formed by the web 24 and flanges 29 is an adjusting link 30, provided with a series of apertures 31. A pin 32 is passed through a preferred one of each of the series of apertures 28 and 31 and prevents endwise movement of the link in the channel. After the required adjustment of the rocker members has been effected as last described, a lag-screw 33 is passed through other regis- 105 tering apertures 28 and 31 and its point threaded into the car end as a fulcrum for the rocker. The bar 20 is pivoted to the upper end of the link 30, and the bar 21

to the lug 25, the pitman being pivoted in the swivel 27 in any suitable manner.

Assuming the parts to be in the relative positions shown at Fig. 1, the operator, standing at either side 5 of the car and entirely free therefrom, will draw on either bar 20 or 21, whereby the rocker will move counter-clockwise and the lever will act on the valve-stem 12 to shut off the air. Too great movement in either direction is prevented by reason of the lug 14 10 striking against an abutment 11 in an evident manner. The swivel-yoke effectually prevents binding or sticking of the pitman. Other advantages of the invention will be apparent and the operation understood from the foregoing description, it being particularly noted 15 that various changes may be made in the details of construction without departing materially from the essential spirit of the invention.

Having thus set forth the construction and operation, the purposes and advantages of the invention, I 20 claim as new and desire to secure by Letters Patent the following, to wit—

1. The combination in a device of the character described, with a valve-stem, of means adapted to reciprocate it, and adjustable means engaged with said means and 25 with a car and adapted to oscillate the first named means.
2. The combination in a device of the character described, with a valve-stem, of means adapted to reciprocate it, means for limiting the extent of movement thereof, and adjustable means attached to said last named means and 30 to a car and adapted to oscillate the first named means.
3. The combination in a device of the character described, with a valve-stem, of means adapted to reciprocate it, a pitman pivoted thereto, an adjustable rocker to which the pitman is pivoted, and means for actuating said 35 rocker.
4. The combination in a device of the character described, with a valve-stem, of means adapted to reciprocate it, a pitman pivoted thereto, an adjustable rocker to which the pitman is pivoted, and means pivoted to the rocker, 40 extending across a car end and adapted to actuate the rocker.
5. The combination in a device of the character described, of an air-cock including a valve-stem, of eccentric 45

means adapted to engage said stem, a pitman pivoted to said eccentric means, a rocker fulcrumed on the car, means 50 for pivotally connecting it and the pitman, and an actuating bar pivoted to each end of the rocker.

6. The combination in a device of the character described, of an air-cock including a valve-stem and abutments, a lever adapted for engagement with said stem 55 and to be limited in its movements by said abutments, a pitman connected to said lever, a rocker including a swiveled member to which the other end of the pitman is secured, and means pivoted to each end of the rocker for actuating it.

7. In combination in a device of the character described, with a valve stem, of a lever adapted to actuate it, an adjustable rocker fulcrumed on the car and pivoted to the lever, and means adapted to be operated from the sides of the car for actuating the rocker.

8. In combination, a valve-stem, eccentric means secured thereto, a rod pivoted to the eccentric means, adjustable oscillatory means to which the rod is pivoted, and means whereby said oscillatory means is actuated.

9. In a device of the character described, in combination, a member adapted to engage the valve-stem, a rod adapted to actuate said member, adjustable rocking means to which the rod is pivoted, and bars adapted to be actuated by hand and to actuate said rocking means.

10. In a device of the character described, in combination, an eccentric member adapted to engage the valve-stem, a rod adapted to actuate said member, adjustable rocking means to which the rod is pivoted, and bars adapted to be actuated by hand and to actuate said rocking means.

11. The combination with a valve stem, of an actuating member having an aperture adapted for engagement therewith, a rocker, means intermediate the actuating member and rocker for actuating the former, and means whereby the rocker may be actuated by hand.

12. A device for operating angle-cocks comprising a horizontally disposed stop-cock with a horizontally disposed and movable lever, a rocker adapted to impart movement to said lever, and reciprocating means extending from the sides of the car for actuating said rocker.

In testimony whereof I hereunto affix my name this 10th day of June, 1907, in presence of two witnesses.

ARCHA FRAVOR.
